US00D704511S

(12) United States Design Patent
Beckman et al.

(10) Patent No.: US D704,511 S
(45) Date of Patent:  May 13, 2014

(54) DRIP TRAY

(71) Applicant: Target Brands, Inc., Minneapolis, MN (US)

(72) Inventors: Jennifer Beckman, Brooklyn Park, MN (US); Rebecca Robledo, Minneapolis, MN (US); Megan Lee, North Oaks, MN (US); Samuel Silva, Coon Rapids, MN (US)

(73) Assignee: Target Brands, Inc., Minneapolis, MN (US)

() Term: 14 Years

(21) Appl. No.: 29/476,828

(22) Filed: Dec. 17, 2013

(51) LOC (10) Cl. 07-01
(52) U.S. Cl.

USPC D7/552.2
(58) Field of Classification Search

(57) CLAIM

The ornamental design for a drip tray, as shown and described.

DESCRIPTION

FIG. 1 is a front, perspective view of a drip tray showing a first embodiment of our new design;

FIG. 2 is a front view thereof, the rear view being a mirror image of the front view;

FIG. 3 is a right side view thereof, the left side view being a mirror image of the right side view;

FIG. 4 is a top view thereof;

FIG. 5 is a bottom view thereof; and,

FIG. 6 is a front, perspective view thereof illustrated with additional, unclaimed environmental subject matter.

The features shown in broken lines are holes of the drip tray or environmental subject matter to the drip tray forming no part of the claimed design.

1 Claim, 5 Drawing Sheets
